DESIGN FOR A MECHANICAL TOY

Ernest K. Steiner, Dayton, Ohio

Application January 30, 1934, Serial No. 50,562

Term of patent 7 years

To all whom it may concern:

Be it known that I, ERNEST K. STEINER, a citizen of the United States, residing at Dayton, in the county of Montgomery and State of Ohio, have invented a new, original, and ornamental Design for a Mechanical Toy, of which the following is a specification, reference being had to the accompanying drawing, forming part thereof.

In the drawing, Fig. 1 is a perspective view of my mechanical toy; and Fig. 2 is a top plan view of the same.

The leading features of this design consist of a polygonal base in dark earth color with a

central turret coated with a sparkling substance, and supporting a circular turntable of a complementary primary color, on which turntable are mounted lifelike figures of quadrupeds in representative colors, and surmounted by a fabric canopy in variegation, that is disposed over illuminants whose light rays are cast on the sparkling surface of the turret and among and about the quadrupeds.

I claim:

The ornamental design for a mechanical toy substantially as shown and described.

ERNEST K. STEINER.
